* cited by examiner

Primary Examiner — Manpreet Matharu*Assistant Examiner* — Lisa A Grabenstetter(74) Attorney, Agent, or Firm — Andrew J. Hagerty(57) CLAIM

The ornamental design for a top sheet for a sanitary napkin, as shown and described.

DESCRIPTION

The patent or application file contains at least one drawing executed in color. Copies of this patent or patent application publication with color will be provided by the Office upon request and payment of the necessary fee.

The sole FIGURE is a top plan view of a top sheet for a sanitary napkin showing our new design.

The broken line portions of the sole FIGURE show unclaimed subject matter only and form no part of the claimed design.
